United States Patent Office.

GEORGE A. WHITCOMB, OF MORRISON, ILLINOIS.

Letters Patent No. 94,160, dated August 24, 1869.

IMPROVEMENT IN MILK-COOLER.

The Schedule referred to in these Letters Patent and making part of the same.

To all whom it may concern:

Be it known that I, GEORGE A. WHITCOMB, of Morrison, in the county of Whitesides, and in the State of Illinois, have invented certain new and useful Improvements in Milk-Cooler; and do hereby declare that the following is a full, clear, and exact description thereof, reference being had to the accompanying drawings, and to the letters of reference marked thereon, making a part of this specification.

The nature of my invention consists in the construction of a milk-cooler, and in the arrangement of certain devices hereafter set forth and explained.

Figure 1 is a plan view of my cooler.

Figure 2 is a sectional view of the same.

Letter A represents a vessel of cylindrical or any convenient shape, which acts as a reservoir for water, in which the second cylinder B is wholly or partly submerged.

These vessels may be of any desired size, and can be formed either of some metallic substance or wood.

Inside of the cooler B there is placed a third vessel, C, which is intended to be filled with water, so as to have it on both the inner and outer sides of the milk, which is placed in the cooler B.

This cylinder C can be taken or removed from the cooler at pleasure, so that the cooler can be cleaned, and has one or more pipes, D, leading into it; so that water can be introduced.

A single pipe will answer for this purpose, made to extend up through the strainer E, or there may be two, so as to allow the air to escape from one while the water is being introduced through the other.

Extending from the bottom of the cooler B, and running out through the side of the reservoir A, there is a pipe, F, which should be provided with a faucet, so that the milk, after being cooled, can be drawn off.

Placed over the top of the cooler B is the strainer E, through which the milk is introduced into the cooler.

The cylinder C and cooler are connected by a hollow burr or nut, which, when they are screwed together, allows the water in the reservoir A to flow in and fill the cylinder.

The strainer acts as a cover, and in use, a cover or flange will extend from the top of the strainer to the top or edge of the reservoir, having an inside rim, so as to hold the cooler in place. Thus the tops of the reservoir and strainer are brought on a level, nearly submerging the strainer, which tends to cool the surplus milk remaining in it.

Having thus described my invention,

What I claim, and desire to secure by Letters Patent, is—

The arrangement of the detachable funnel-shaped strainer E, the jacket d, and circumferential flange a, reservoirs A C, cooler B, and pipes D F, all constructed and operating as set forth.

In testimony that I claim the foregoing, I have hereunto set my hand, this 29th day of April, 1869.

GEO. A. WHITCOMB.
